UNITED STATES PATENT OFFICE.

WILLIAM S. WHITING, OF WATERBURY, CONNECTICUT, ASSIGNOR TO
CHARLES F. TROTT, OF SAME PLACE.

DESIGN FOR A SMOKER'S SET.

SPECIFICATION forming part of Design No. 19,103, dated May 14, 1889.

Application filed January 28, 1889. Serial No. 297,833. Term of patent 7 years.

To all whom it may concern:

Be it known that I, WILLIAM S. WHITING, a citizen of the United States, residing at Waterbury, in the county of New Haven and 5 State of Connecticut, have invented and produced a new and original Design for a Smoker's Set; and I do declare the following to be a full, clear, and exact description of the same, reference being had to the accompanying drawing, forming a part thereof, in which the figure is a perspective of my novel smoker's stand in the closed position.

My novel design consists of a representation of a log cabin having a stone chimney, 15 bark roof, &c. The sides of the cabin are formed to imitate rough-hewn logs joined at the corners in the traditional manner. At one end of the cabin is a representation of a rough stone chimney. The roof is a representation of strips of bark laid in the 20 traditional manner. The door represents rough boards, and in the foreground is placed the traditional cider-barrel, also the representation of a rock.

1 denotes the end of the log cabin; 2, the front, and 3 the door, represented as formed of rough boards; 4, the roof, represented as formed of strips of bark the sides of which are overlapping, so that the strips set at an angle, the succeeding row of strips being inclined in the opposite direction; 5, the chimney, which contains a receptacle, 6; 7, a representation of a cider-barrel; 8, a representation of a rock, and 9 the base, to which the parts are firmly secured.

35 What I claim is—

The design for a smoker's set, consisting of the representation of a log cabin and a base on which said cabin rests, substantially as shown and described.

40 In testimony whereof I affix my signature in presence of two witnesses.

WILLIAM S. WHITING.
